UNITED STATES PATENT OFFICE

141,759

DESIGN FOR A GAME BOARD

Fred Linn Gamblin, Dora, Ala.

Application March 16, 1945, Serial No. 118,517

Term of patent 14 years

(Cl. D34—5)

To all whom it may concern:

Be it known that I, Fred Linn Gamblin, a citizen of the United States, residing at Dora, in the county of Walker and State of Alabama, have invented a new, original, and ornamental Design for a Game Board, of which the following is a specification, reference being had to the accompanying drawing, forming part thereof.

I claim:

The ornamental design for a game board as shown.

FRED LINN GAMBLIN.
